UNITED STATES PATENT OFFICE.

SIBYL A. SCOTT, OF NEW YORK, N. Y.

BLOCK-PACK.

1,394,363.

Specification of Letters Patent. Patented Oct. 18, 1921.

Application filed November 26, 1920. Serial No. 426,663.

To all whom it may concern:

Be it known that I, SIBYL A. Scott, a citizen of the United States, and a resident of the city of New York, borough of Manhattan, county and State of New York, have invented certain new and useful Improvements in Block-Packs, of which the following is a full, clear, and exact description.

Among the principal objects which the present invention has in view are: To provide a pack of leveling devices held intact without necessitating containers therefor; to distribute articles of the character mentioned in small packs of uniform number; to reduce the labor factor incident to packing said articles; to expose the article for view without impairing the pack; and to maintain the disposition of various articles of the pack in alinement.

Drawings.

Figure 1 is a perspective view of a pack constructed and arranged in accordance with the present invention.

Fig. 2 is a longitudinal section thereof.

Fig. 3 is a perspective view showing one of the articles held in the said pack.

Description.

The wedge shaped blocks 8 shown in the drawings are employed principally for leveling tables in restaurants and other places, and to this end are carried by the waiters employed in the restaurants and by the customers of the restaurants. They are for convenience sold on the markets in the form of solid blocks as shown in Fig. 1 of the drawings.

For convenience the blocks 8 are extracted from the pack successively. The separation of each block is facilitated by removing the key ball 9 which is accomplished by releasing the tie 10 of the thread 11.

The thread 11 is passed through the perforations 12 one of which is provided in each block in alined relation with all of the perforations in the other blocks, as seen best in Fig. 2 of the drawings. When the blocks are disposed as seen best in Fig. 2 of the drawings a straight channel is formed by the various perforations 12 through which the thread 11 is extended. The thread 11 is looped and at the end of the loop a master ball 13 is mounted. The opposite end of the

loop is passed through the perforation in the 55 key ball 9 and tied in any convenient and suitable manner.

To prevent the blocks 8 rotating about the channel formed by the perforations 12, a label 14 is pasted on the pack, as is seen best 60 in Fig. 1 of the drawings. The dimensions of the label 14 equal the dimensions of one side of the pack. The surface of the label adhering as it does to the butts of the wedge blocks 8 as shown best in Fig. 2 of the drawing, prevents the rotation not only of the blocks thus adhered, but also of the blocks interleaved therewith.

The label 14 serves the useful purpose of carrying the name, trade mark, and directions, for use of the blocks 8 and is used to instruct as to the best method of removing each block from the pack. This is accomplished by releasing the tie 10 and then removing from the pack the endmost block 8. 75 As each block is removed from its neighbor block, it is used to tear the label 14 with which it is associated. After the required number of blocks 8 have been removed, the key ball 9 is replaced on the thread 11 which 80 is then tied to prevent the removal of the said key ball. The remaining blocks 8 will then be found exceedingly convenient for general use and save a great deal of annoyance which arises from a tittering or rocking table so often encountered in the usual restaurants. The blocks may be also used for purposes of silencing loose windows in sashes, or doors in frames.

While I have herein shown the blocks 8 as 90 constructed from wood, it will be understood that other suitable material may be employed which will serve the same purpose and will prove sufficiently durable to withstand rough usage to which such blocks are 95 subject in service.

Claims.

1. A block pack comprising a plurality of wedge-shaped interleaved members, the 100 butts of adjacent members being turned in the opposite direction; and means adhered to the said butts for maintaining said members in fixed relation, said means embodying a fibrous pasteur adhesively secured to said 105 pack and to the butts of the members forming one side of said pack.
2. A block pack comprising a plurality of

wedge-shaped interleaved members, the butts of adjacent members being turned in the opposite direction; means adhered to the said butts for maintaining said members in fixed relation, said means embodying a fibrous paster adhesively secured to said pack and to the butts of the members forming one side of said pack; and means for holding said members in permanent juxtaposition.

3. A block pack comprising a plurality of wedge-shaped interleaved members, the butts of adjacent members being turned in the opposite direction; means adhered to the said butts for maintaining said members in fixed relation, said means embodying a fibrous paster adhesively secured to said pack and to the butts of the members forming one side of said pack; and means for holding said members in juxtaposition, said means embodying a series of perforations, one in each of said blocks, said perforations being

disposed in alined relation, and a threading member extended through said perforations.

4. A block pack comprising a plurality of wedge-shaped interleaved members, the butts of adjacent members being turned in the opposite direction; means adhered to the said butts for maintaining said members in fixed relation, said means embodying a fibrous paster adhesively secured to said pack and to the butts of the members forming one side of said pack, and means for holding said members in juxtaposition, said means embodying a series of perforations, one in each of said blocks, said perforations being disposed in alined relation, and a threading member extended through said perforations; and anchoring means for said tie member embodying threaded balls at the opposite ends of the loop formed by said tie member.

SIBYL A. SCOTT.
